(57) **CLAIM**

The ornamental design for a fence post collar to inhibit vegetation and wood rot, as shown and described.

DESCRIPTION

FIG. 1 is a perspective view of a fence post collar to inhibit vegetation and wood rot showing my new design;

FIG. 2 is a side elevational view thereof;

FIG. 3 is a top plan view thereof;

FIG. 4 is bottom plan view thereof.; and,

FIG. 5 is detail view showing the edge of FIG. 3 thereof.

The fence post of the fence post collar to inhibit vegetation and wood rot is shown in broken lines for illustrative purposes only and form no part of the claimed design.
